CIGAR-LIGHTER

Joseph H. Cohen, Bridgeport, Conn.

Application November 20, 1928

Serial No. 320,661

6 Claims. (Cl. 219—32)

This invention relates to cigar lighters, and more particularly to an improved holding device for cigar lighters of the type having a removable igniting unit.

- 5 An object of this invention is to provide a holding device for cigar lighter and igniting units which is simple in construction and yet strong and durable in use. This and other ancillary objects are accomplished by the novel construction and arrangement of parts as fully described and claimed in the accompanying specification, in which—

15 Figure 1 is a longitudinal sectional view through the holding device of the present invention, showing in section an instrument board made of wood.

Fig. 2 is a perspective view of the device of the present invention, showing a metal instrument-board in dot-and-dash lines.

20 Fig. 3 is a sectional view of the bracket, showing the escutcheon plate and post secured in place thereon.

Fig. 4 is a front view of the bracket, before the escutcheon plate and post are mounted in position.

Fig. 5 is a sectional view of the post which carries the igniting unit.

Fig. 6 is a perspective view of the escutcheon plate.

30 The device of the present invention comprises an igniting unit 10, shown in dot-and-dash lines, adapted to be removably supported on a holding device 11 which may be attached to an instrument-board 12 of a motor vehicle or the like.

35 The igniting unit 10 shown may be of any suitable construction, such, for instance, as is shown in my copending application, Serial No. 304,745.

It is adapted to be removably supported on a post 13 forming part of the holding device 11, the 40 post 13 having a sleeve or cap 14 which is directly engaged by means on the igniting unit 10 and which carries a contact 15 insulated therefrom.

The sleeve 14 is slidably mounted on the post 13 and is normally held in the position shown in

45 Fig. 1 by a spring 16 so that an inner point 17 of the contact 15 is held out of engagement with a contact 18 supported by the post and having soldered, in a central bore thereof, an end 19 of a feed-wire 20. The contact 18 is insulated from

50 the post 13 by a sleeve 8 of insulating material which is forced into the central bore in the post. This construction is described and claimed in my copending application, Serial No. 254,962 now Patent No. 1,710,531, April 23, 1928.

55 As is shown in the patent last referred to and

as was customary in the art prior to the present invention, the post 13 was provided with an extension adapted to be passed through a hole drilled in the instrument-board, and the device of the present invention is an improvement thereover, since by its provision the holding device may be clamped to the instrument-board without drilling any holes in the latter. For this purpose, the present invention provides a bracket 21 made of sheet metal and bent U-shape so as to have a front arm 22 and a rear arm 23, the former being adapted to engage the front of an instrument-board or the like, and the latter being provided with a screw 24 which may be turned so that its point 25 will engage the back edge of the instrument-board and draw the front arm 22 tightly against the front face thereof. The rear end of the screw 24 is provided with a knurled head 26 to facilitate its rapid rotation by hand when adjusting the screw, and the head 25 is provided with a kerf 27 to receive the end of a screw driver or other similar instrument to firmly tighten the screw.

To secure the post 13 firmly to the front arm 22 of the bracket, the latter is provided with a circular hole 28 and this is countersunk at 29, see Figs. 1 and 4, so as to receive a flange 30 on the post 13 when the post is inserted from the rear in the hole 28, thus permitting the rear end of the post to lie flush with the rear surfaces of the arm 22. The flange 30 is formed on a head or enlargement 31 on the post, adjacent the forward end of which there is initially formed a ring 32, see Fig. 5, which is deformed by spinning or pressing after the device is assembled to rigidly hold the post 13 on the front arm 22 of the bracket.

However, before the ring 32 is spun over from the position shown in Fig. 5 to that shown in Fig. 1, an escutcheon plate 33 which has a circular hole 34 is slid over the enlarged portion 31 of the post and placed flat up against the front arm 22 of the bracket, so that when the ring 22 is spun over the post 13, the front arm 22 and the escutcheon plate 33 form an entity which cannot be disassembled without destroying the device itself.

In order that the escutcheon plate may conceal as much as possible of the bracket, and in order to prevent rotation of the escutcheon plate on the portion 31 of the post which would tend to loosen the same, the escutcheon plate is provided with a notch 35, see Fig. 6, in which the arm 22 is located. The notch 35 is formed in the edge 36 of the escutcheon plate and hence the edge 105

may lie firmly against the front face of the instrument-board when the screw 24 is tightened. The escutcheon plate is provided with an embossed portion 37 adapted to surround the inner 5 end of the igniting unit 10, and prevents a person operating the same from getting his finger caught beneath the end of the igniting unit when the latter is pushed inwardly to bring the contact point 17 in engagement with the contact 10 point 18.

In order to permit passage of the wire 20 from the center of the post to some point in the instrument-board where it may be connected to the current supply without unduly pinching the same, 15 the enlarged portion 31 of the post is provided with a slot 38 adapted to align with a slot 39 formed in the front arm 22 of the bracket so that the wire may be brought down through the slots, as shown in Fig. 1, to prevent chafing of the wire 20 between the front face of the instrument board to the escutcheon plate and post. The slot 39 is continued through a slot 39a in the horizontal portion of the bracket 21 and thus the wire 20, when located in the slots, will be unnoticeable 25 by the occupants of the car, but, of course, the slot may terminate at the intersection of the front arm 22 and horizontal portion of the bracket if desired.

In Fig. 1, the device is shown as attached to an 30 instrument-board 12 made of wood. Since the return circuit for the device is constituted by the shell 14, post 13 and bracket 21, the present invention provides on the rear arm 23 of the bracket a binding screw 40 in which the end of a ground 35 wire 41 may be secured. Of course, when the device is attached to the metallic instrument-board 12a, shown in Fig. 2, it is unnecessary to have the ground wire 41, for even should the paint on the instrument-board tend to insulate the bracket 40 and escutcheon plate from the instrument-board, the end 25 of the fastening screw 24 will pierce the same and make good metallic and electrical connection therewith.

Variations and modifications may be made 45 within the scope of this invention, and portions of the improvements may be used without others.

Having thus described the invention, what is claimed as new and for which it is desired to obtain Letters-Patent, is:—

50 1. A holding device for cigar-lighter igniting units comprising a bracket formed of a sheet metal strip bent to provide a U-shaped piece having front and rear vertically extending arms; a cylindrical post secured to the front arm and 55 adapted to removably support an igniting unit, said post being adapted to pass through a circular hole in the front arm and having a pair of flanges each greater in diameter than the hole in the bracket arm, at least one of said flanges being formed after the post is assembled in the bracket arm; and an escutcheon plate formed so that the edge thereof may engage and lie flat against an instrument board, said plate being interposed between one of the flanges on the post 60 and the front arm of the bracket and being securely held to the post and arm thereby, the edge of the plate being provided with a notch in which the front arm of the bracket may lie, the walls of the notch engaging the edges of the front arm

to prevent the escutcheon plate from turning on the post.

2. A holding device for cigar-lighter igniting units comprising a U-shaped bracket having front and rear vertically extending arms; a post secured to the front arm and adapted to removably support an igniting unit; an escutcheon plate on said post; a contact on said post; and a pig-tail secured to said contact, said pig-tail being covered with insulating material and being adapted to extend rearwardly through said post, said post and bracket being provided with clearance passages to permit said pig-tail to extend between the instrument-board and the escutcheon plate.

3. A holding device for cigar-lighter igniting units comprising a U-shaped bracket having front and rear vertically extending arms; a post secured to the front arm and adapted to removably support an igniting unit; an escutcheon plate on said post; a contact on said post; and a pig-tail secured to said contact, said pig-tail being covered with insulating material and being adapted to extend rearwardly through said post, said post and bracket being provided with clearance passages to permit said pig-tail to extend between the instrument-board and the escutcheon plate, the body of the bracket being provided with a longitudinally extending slot in which the pig-tail may lie when extending rearwardly under 105 the instrument-board.

4. A holding device for a cigar-lighter igniting unit comprising a U-shaped bracket having front and rear vertically extending arms, the former being adapted to lie against the front face of an instrument board and the portion between the front and rear arms being adapted to lie against the lower edge of the instrument board; and means on the front arm adapted to removably support an igniting unit, said bracket being provided in its front arm and the portion between the front and rear arms with vertical and longitudinal wire clearance passages respectively, so that a current supply wire leading to said means may lie adjacent the instrument board.

5. A holding device for a cigar-lighter igniting unit comprising a U-shaped bracket having front and rear vertically extending arms, the former being adapted to lie against the front face of an instrument-board and the latter being provided with screw means for drawing the front arm against the instrument-board, the front arm of the bracket having a countersunk hole; and a post having at one end a head fitting said countersunk hole so as not to protrude beyond 130 the rear surface of the front arm.

6. A holding device for a cigar-lighter igniting unit comprising a U-shaped bracket having front and rear vertically extending arms, the former being adapted to lie against the front face of an instrument-board and the latter being provided with screw means for drawing the front arm against the instrument-board, the front arm of the bracket having a countersunk hole; and a post having at one end a head fitting said countersunk hole so as not to protrude beyond the rear surface of the front arm and said post having a flange embracing the front surface of the front arm.
